(57) **CLAIM**

We claim the ornamental design for a metal detector, as shown and described.

DESCRIPTION

1. Metal Detector

FIG. 1.1 is a front isometric view of a portable locator in a deployed position;

FIG. 1.2 is a front isometric view from above in a stowed position;

FIG. 1.3 is a rear isometric view from above in a stowed position;

FIG. 1.4 is a rear isometric view from below in a stowed position;

FIG. 1.5 is a front isometric view in a retracted and deployed position;

FIG. 1.6 is a rear isometric view in a retracted and deployed position; and

FIG. 1.7 is a rear isometric view from below in a retracted and deployed position.
